INVENTOR
ANTOINE TRUFFY,
BY ATTORNEYS.

UNITED STATES PATENT OFFICE.

ANTOINE TRUFFY, OF COURBEVOIE, FRANCE.

FOLDING SEAT.

Application filed February 20, 1920. Serial No. 360,250.

To all whom it may concern:

Be it known that I, ANTOINE TRUFFY, a citizen of the Republic of France, and a resident of 15 Impasse Parmentier, Courbevoie, Seine, France, have invented new and useful Improved Folding Seats, of which the following is a specification.

This invention has for its object to provide an improved folding seat, characterized 10 by the feature that the legs of the seat constitute the branches of a jointed X, one of these branches being pivoted to the seat proper, whereas the other branch is pivoted to the back, which latter is likewise pivoted 15 to the seat proper, the locking of the said branch to the back being effected by means of any suitable device.

A seat according to this invention is illustrated by way of example in the accompanying drawings in which:

Fig. 1 is a side elevation of the seat in its opened condition.

Fig. 2 is a side elevation of the seat when closed.

Fig. 3 is a partial section on the line 3—3 of Fig. 3.

At the lower front part of the seat proper *a* there are mounted two angles *b* to which is pivoted one of the branches *c* of the X, the other branch *d* being pivoted to the fitting *e* which constitutes the support for the back *f*. The branches *c* and *d* are pivoted to each other by means of a pivot member *g*.

The fitting *e* is pivoted at *h* to an angle *i* fixed to the upper rear part of the seat proper *a*.

Each of the branches *c* and *d* consists of a sort of fork of steel tubing. The ends of the tubes that constitute the branch *c* 40 form the rear legs of the seat, whilst those of the tubes of the branch *d* constitute the front legs.

The means for locking the branch *d* to the fitting *e* consists for instance of a pivot member *j* journalled in the two side plates of the fitting *e* and formed with two "flats" *k*.

This pivot member *j* is adapted to engage, when the seat is open, in notches *l* formed 50 in the ends of the tubes constituting the branch *d*. A rotational movement through about 90° prevents the pivot member *j* from

slipping out of the notches *l*, and thus fixes the branch *d* relatively to the back *f*.

This seat which may be used as a folding 55 seat in motorcars, boats, etc., may be fixed to the floor on which it rests by means of grooved plates into which the ends of the legs are inserted.

It is to be understood that this invention 60 is not limited to the constructional details that have just been described, thus for instance the means of locking the legs to the back may be varied, and this method of pivoting the legs may be applied to all kinds 65 of seats.

Having now particularly described and ascertained the nature of my said invention and in what manner the same is to be performed, I declare that what I claim is:— 70

1. A folding seat, comprising a seat proper, a back pivoted to the rear of said seat proper, legs pivotally connected in a non-detachable manner and forming the branches of a jointed X, one of said branches 75 being pivoted to the fore part of the seat proper, and the other branch to a downward extension of the back, at a point nearer to the connection between the seat proper and the back than to the pivot point of the two 80 branches of the leg, for the purpose described, the ends of the said branches being provided with notches, and a revoluble member mounted in the back and having flattened portions to permit it to enter the 85 notches and to be retained in said notches.

2. A folding seat, comprising a seat, a back pivoted to the seat, legs having branches at their ends and pivoted together, the branches of one leg being pivoted to the 90 seat and the branches of the other leg being pivoted a short distance from their ends to the back, the ends of the said branches being provided with notches, and a revoluble member mounted in the back and having flattened portions to permit it to enter the 95 notches and to be retained in said notches.

In testimony whereof I have signed my name to this specification.

ANTOINE TRUFFY.
